UNITED STATES PATENT OFFICE.

GEORGE ALBERT, OF SALIDA, COLORADO.

SHOVEL-HANDLE EXTENSION.

1,081,187.

Specification of Letters Patent.

Patented Dec. 9, 1913.

Application filed January 14, 1913. Serial No. 741,976.

To all whom it may concern:

Be it known that I, GEORGE ALBERT, a citizen of the United States, residing at Salida, in the county of Chaffee and State 5 of Colorado, have invented new and useful Improvements in Shovel-Handle Extensions, of which the following is a specification.

This invention relates to extensible handles and particularly to handles designed for use on shovels generally used by locomotive firemen or the like; and it has for an object the provision of a handle of this character which may be conveniently connected with the regular handle of the shovel so that required extension of the shovel may be made to facilitate scooping the coal after the latter reaches a remote point in the tender or tank and to also employ such form of extensible handle which can be removed from the main handle with facility when it is desired to employ a handle of comparatively short length.

A further object of the invention is the provision of coöperating companion clamping plates which are adapted for locking engagement against the opposite sides of the main handle and means connecting the plates whereby to effectually retain the extensible handle in proper relative position to the main handle.

Another object of the invention is to provide an adjusting element which will be connected with the companion clamping plates in such manner as to positively prevent the plates from loss or accidental separation when the extensible handle is removed from the main handle.

With these and other objects in view, the invention consists of certain novel features of construction, combination and arrangement of parts, as will be hereinafter described and claimed.

In the accompanying drawings:—Figure 1 is a perspective view of a shovel, showing the application of the extensible handle thereto; Fig. 2 is a longitudinal section therethrough; Fig. 3 is a similar view, showing the companion clamping plates adjusted relatively whereby to permit the extensible handle to be readily removed from the main handle; Fig. 4 is a perspective view of the blank from which the hand gripping portions of the plate of the extensible handle is formed; Fig. 5 is a perspective

view of the gripping portion of the main handle, showing the toothed surface thereof; Fig. 6 is a perspective view of the other plate element of the extensible handle; and Fig. 7 is a section on line 7—7 of Fig. 1. 60

The shovel 1 herein illustrated is of the standard construction generally employed by locomotive firemen or the like, the shovel being shown to include a scoop 2 and a handle 3, the latter terminating in a grip 65 4 having a finger receiving passage 5 and a main hand gripping bar 6.

The extensible handle comprises companion clamping plates 7 and 8 of relatively different lengths, the plate 7 being split 70 preferably in its main length and then bent at right angles to the plane of the main clamping portion thereof so as to provide longitudinally extending spaced side bars 9, which are connected at their outer ends 75 by a grip 10. At the immediate point of connection of the side arms 9 with the main body of the plate 7, the arms are curved so as to present embracing portions 11, which are adapted to lie in mutual contact with 80 the outer surface of the gripping bars 6 of the main handle. The plate 8 is correspondingly curved at 12 to partly embrace the grip 6, while at the opposite end the plate 8 is curved inwardly at 13 and provided with biting teeth 14, which are adapted 85 to coöperate with similar teeth 16 on the curved end 17 of the plate 7 and engage the body 11 of the grip on the main handle of the shovel. This construction is such that 90 when the companion plates are in proper clamping contact with the opposite sides of the main handle of the shovel, the extensible handle will be properly connected with the main handle whereby to materially increase 95 the length of the shovel structure.

The plate 8 is provided with a longitudinal slot 18, which is aligned with an opening 20 in the plate 7. Said opening 20 has extended therethrough a screw 21, which is 100 provided at one end with a manipulating head 22, which is adapted to lie in mutual contact with the outer face of the plate. Said manipulating head has a kerf 23 for the reception of a suitable operating tool, which may be manipulated to permit the screw to be fed in a longitudinal direction in the receiving socket 24. The receiving socket is extended through the elongated slot 18 and is preferably provided with a 105 110

rectangular portion 25 which is associated with adjacent walls of the slot so that the latter forms stops to hold the sockets against rotation during the adjusting operation of 5 the screw. The screw is accommodated in the socket by a thread 26 which receives the thread of the screw, and as illustrated the threaded bore of the socket is in open communication with a large smooth bore 27, 10 the formation of the inner walls of the socket at the juncture of the bore 27 with the threaded bore of the socket is such as to provide an intervening stop shoulder 28. The bore 27 accommodates an upset portion 15 or head 29 of the screw, the latter being adapted to engage against the stop shoulder whereby to limit the relative longitudinal adjustments of the screw and the socket. The socket 24 is provided with a relatively 20 large head 30, which is adapted to engage against the outer face of the plate 7 so that the latter and the companion plate 8 may be brought to properly bear against the opposite sides of the main handle and thereby 25 insure a proper connection between the latter and the extensible handle.

The plate 8 has its slot 18 terminating at different distances from the opposite ends of the plate, whereby said plate may be 30 turned to the position shown in Fig. 3 to permit of the passage thereof through the finger receiving opening 5 in the main handle when the screw 21 is adjusted to one position and thereby effect relative positions 35 of the companion plates to permit the extensible handle to be conveniently removed from the main handle. The adjusting connection between the companion clamping plates is of such form as to prevent the 40 casual separation or displacement of the plate from the connection when the extensible handle is removed.

The side bars 9 of the gripping portion of the extensible handle are preferably pressed 45 in their main length whereby to possess substantially a concavo-convex configuration transversely and thereby increase the rigidity of said arms.

From the foregoing description, taken in 50 connection with the accompanying drawings, the construction and operation of the invention will be readily understood without requiring a more extended explanation.

Various changes in the form, proportion 55 and the minor details of construction may be resorted to without departing from the principle or sacrificing any of the advantages of this invention, as claimed.

Having thus described my invention, what 60 I claim is:—

1. A shovel provided with a fixed handle, and an extensible handle including a gripping portion lying parallel with the gripping portion of the fixed handle and includ- 65 ing companion clamping portions adjustable

against the opposite sides of said fixed handle.

2. A shovel provided with a fixed handle, an extensible handle including a gripping portion lying parallel with the gripping portion of the fixed handle and including companion clamping portions adjustable against the opposite sides of said fixed handle, and a connecting element extending through the fixed handle and connecting the 75 clamping portions.

3. A shovel provided with a fixed handle, an extensible handle including a gripping portion lying parallel with the gripping portion of the main handle and including 80 companion clamping portions adjustable against the opposite sides of said main handle, a connecting element extending through the main handle and connecting the clamping portions and comprising threadedly connected members and means for holding the members against relative separation on adjustment of the members to prescribed positions.

4. A shovel provided with a fixed handle 90 having a gripping portion and a hand receiving opening, and a removable handle having a gripping portion lying parallel with the gripping portion of the fixed handle and including clamping portions lying 95 against the opposite sides of the fixed handle and an adjusting element extending through the hand receiving opening of the fixed handle.

5. A shovel provided with a fixed handle 100 having a hand receiving opening and a gripping portion, clamping plates disposed at the opposite sides of the fixed handle and having toothed surfaces operable to engage therewith, and a clamping device extending 105 through the handle receiving portion of the fixed handle and operatively connected with the companion plates whereby to adjust the plates with relation to the opposite sides of said main handle.

6. A shovel provided with a fixed handle having a hand receiving opening and a gripping portion, clamping plates disposed at the opposite sides of the fixed handle and having toothed surfaces operable to engage 115 therewith, and a clamping device extending through the handle receiving portion of the fixed handle and operatively connected with the companion plates whereby to adjust the plates with relation to the opposite sides of said main handle, one of the plates being mounted for sliding movements on the clamping device and adapted to be adjusted whereby to be withdrawn through the hand receiving opening.

7. A shovel provided with a fixed handle having a hand receiving opening and a gripping portion, clamping plates disposed at the opposite sides of the fixed handle and having toothed surfaces operable to engage 130

therewith, and a clamping device extending through the handle receiving portion of the fixed handle and operatively connected with the companion plates whereby to adjust the 5 plates with relation to the opposite sides of said main handle, one of the plates being slidably and rotatably mounted on said device and being adapted when in one position

to be withdrawn through the hand-receiving opening.

In testimony whereof I affix my signature 10 in presence of two witnesses.

GEORGE ALBERT.
